United States Patent Office

Des. 228,825
Patented Oct. 23, 1973

228,825

PAPER CUTTER

Alvin R. Pottern, Longmeadow, Mass., assignor to Milton Bradley Company, East Longmeadow, Mass.

Filed May 16, 1972, Ser. No. 253,917

Term of patent 14 years

Int. Cl. D18—04

U.S. Cl. D95—1 R

FIG. 1.

FIG. 2.

FIG. 3.

FIG. 4.

FIG. 5.

FIG. 6.

FIG. 1 is a top plan view of a paper cutter showing my new design;

FIG. 2 is an end elevational view as seen from the right of FIG. 1;

FIG. 3 is a view similar to FIG. 2 showing the cutting arm in raised position;

FIG. 4 is an end elevational view as seen from the left of FIG. 1, with the cutting arm in raised position;

FIG. 5 is a front elevational view thereof; and

FIG. 6 is a rear elevational view thereof.

I claim:

The ornamental design for a paper cutter, as shown.
